PRINTING TELEGRAPH

Leon Cammen, New York, N. Y.

Application May 26, 1933. Serial No. 672,965

15 Claims. (Cl. 178—33)

The present invention refers to telegraph printers of the nonsynchronous type ("stop-and-start"), and has for its purpose the production of a fast telegraph printer of low initial cost.

5 In the illustrations,

Fig. 1 shows an electromagnet with two windings and resistance;

Fig. 2 shows diagrammatically the electrical circuits of the apparatus;

10 Fig. 3 shows the subsidiary grid;

Fig. 4 is a view in vertical section of the main grid bars and cancellation mechanism;

Fig. 5 is a horizontal section of the apparatus of Fig. 4;

15 Fig. 6 is the mechanism for moving the commutators.

Only the receiving mechanism is shown here, as the matter of the appropriate sending mechanism has been set forth in my other patent application, Printing telegraphs, filed April 12, 1933, 20 Ser. No. 665,633, now pending before the Patent Office.

The operating mechanism consists of type mounted in the usual manner on keys, e. g. such 25 as are used in typewriters, these keys being mounted on a system of levers in such a manner that a pull or pressure on the appropriate lever causes the type face of the key to impinge on a roll or tape of paper, as through an inking ribbon, and print the character. The same mechanism may be used to produce a spacing of letters or words.

The sending station causes groups of impulses, known as the code, to travel along the wire or 30 other conductor, such as 40, and the present invention is concerned exclusively with the apparatus and method that permits a selected group of impulses to operate the key that prints on the paper the letters corresponding to that group 40 of impulses in the code used by the machine. In the present invention two kinds of impulses with some spacing between them are used, and by way of illustration a machine described wherein sixty-four characters or their equivalents may be 45 decoded from six impulses per character. The only requirement as to the impulses is that they should be of two kinds, positive and negative, strong and weak, low or high speed frequency, etc. They shall be denoted here as P and N.

50 The impulse from the sending station comes over wire 40 or similar conductor, such as "ether", and goes to a device, such as a polarized relay, sensitive to the kind of impulses used, such as PN. To show the operation of the device, let it 55 be assumed that the character being sent over

conductor 40 is coded as follows: P—N, N—P, P—P, the signals being divided into three groups of two for reasons that will appear hereafter.

As the first P impulse comes in, the armature 20 is attracted causing the closing of the switch 60 at 21 and thereby establishing the following circuit, the meaning of its constituents to be set forth presently: 21 to 20 to 23 over 24 to 25 to 36 to P27 over 28 to 22 to 495 to SMS to 21.

As the impulse coming over 40 is very weak, 65 it is merely used to close the circuit at 21 which causes a flow of energy into another circuit from an independent source of power 22 which may be of any desired magnitude. Of the other constituent parts of the circuit reference will now 70 be made to the subsidiary grid, Fig. 3. This is essentially a switching device, and consists of two (though a greater number is possible) bars in one set capable of moving, as by motor elements 811 and 812, towards the other set of two bars 75 (813 and 814), producing a circuit closing contact when a bar in one set meets a bar in the other set. For the sake of convenience, the 811 and 812 bars will be referred to as horizontal, and the other two as vertical, P27 of Fig. 2 being the 80 same as 811, N55 as 812, P61 as 813 and N38 as 814. Two impulses can be here used to produce a closing of the circuit at any one of four points desired.

I have next a system of what I have referred 85 to as commutators, of which in the circuit here shown there are seven, 25, 306, etc. They are all mounted on the same shaft and are moved for one-sixth of the appropriate angular distance for each impulse coming over conductor 40. Each 90 commutator consists of a means of bringing the current in, e. g. as by wire 24, a conductor or brush, 25, moved upon every impulse, and an outer contact, such as 36, properly connected into the circuit as will be shown hereafter, each commutator controlling its own circuit in a suitable manner. In the position shown in Fig. 2, the topmost commutator is receiving current flowing from 22 into 24, by the circuit shown in detail previously, whereupon conductor brush 25 permits it to flow into the busbar shown by the dotted line, and thence the current flows to P27. It will be noted that when the brush 25 has been moved to a different position, an entirely different 95 flow of current is instituted.

100 As previously stated, the current passes through SMS which is a switching magnet and when energized, causes the attraction of the armature which then makes contact with 730, and establishes the following circuit: 22 over 728 110

through armature of SMS to 730 to S to M to 595 and back to 22; 495, 595 and 695 are lamps or resistances, and may be eliminated by a proper selection of the windings of the various magnets.

5 The reason for the creation of the circuit through S—M operated by SMS is as follows. As will be shown later, S—M has to exert a considerable amount of power which means that a fairly large current must be sent through it. At 10 the same time, SMS which represents here SM, is at times in series with several other magnets, and at times has very little in series with it. The amount of energy flowing through this particular magnet is therefore apt to become excessive under one set of conditions, or insufficient under another. To take care of this difficult situation, the switching magnet SMS has been introduced. It takes only enough power to close the switch at 730, but permits SM to take at all times all 15 the power it needs from its own circuit through lamp 595.

The action of SM is shown in Fig. 6. As SM is energized, it attracts armature 256 which causes pawl 257 to slide upwards along the ratchet wheel 252 against the tension of spring 252. When, however, the circuit energizing SM is broken, the armature falls off, and spring 252 pulls the ratchet wheel over one step. The commutators are mounted on the same shaft as the ratchet wheel, 20 or on a layshaft geared to the ratchet wheel shaft. It is important to note that the ratchet wheel is moved on the break of the current through SM, and not on the make.

From the explanation of the action of the subsidiary grid it appears that in order for it to act, 35 it is necessary that either 811 or 812 move towards the set of bars 813—814, and that one of these latter move to meet it. This is simple when both selected bars move at the same time, but if one moves first, it must be held until the bar in the other set has a chance to move. In other words, the first-operated bar must be locked in operable position until the second-operated 40 bar has a chance to move. This may be accomplished by any of the known mechanical detents, but is done electrically here in the following manner.

As the current from 36 (uppermost commutator) goes through P27, the latter attracts its armature 301 which moves the subsidiary grid bar 31—32 (811 of Fig. 3). Furthermore, the current from the line 36—P27 also flows into 302 because of the wiring provided but usually the circuit is broken at 304, except when the armature 45 is pulled up and closes the circuit there. The following circuit is then established: 36 to 302 over 301 to 304 over 305 and over 306 to 307 and by wire 44 and lamp 495 to 22. In this way, two currents are flowing through the winding of magnet P27, and if desired, two windings thereon 50 may be provided, as shown in Fig. 1. One of the currents, however, is supplied through 21, which means that it lasts only as long as the impulse coming over conductor 40, and when this ceases, it stops, so that, were it not for the second current, armature 301 would have pulled away, and coordinate bar 31—32 would fall back from its operating position. The second current, however, keeps it locked. The presence of 55 a proper resistance 395 in series with the winding carrying the second, i. e. locking, current is important, as otherwise the circuit becomes unstable, and SM is apt to operate several times on the same impulse. The advantage of using 60 an electrical detent as compared with mechani-

cal detents lies in the elimination of several moving parts and cancellation magnets, all the more undesirable as they have to operate three times for every character, i. e. at extremely small intervals of time.

As the impulse over 40 ceases, the SM magnet is de-energized, and ratchet wheel 252 is moved one step, in turn moving all the commutators one step, to the following positions: 78; 322; 332; 432; 532; 632; 37. The next impulse is N closing switch 34 and establishing the following primary circuit: 34 to 35 over 136 to 29 to 37 to N38 which moves coordinate subsidiary bar 31—58. The current then goes by wire 28 to 22, 495, SMS to 34, concluding the circuit. The closing of the switch at 31—39, at the intersection of the coordinate bars 31—32 and 31—58, operates the motor element 1 on the main grid (the construction and functions of this letter will be explained presently), the current continuing to 31 to 608 to 632 to 1 to 928 to 28 to 22 closing the circuit. SMS is then de-energized by the breaking of the circuit at 34 due to discontinuance of the impulse from the sending station which in turn causes SM to de-energize, and 100 moves the ratchet wheel and commutators to a new position, one step ahead. Among others, 306 is moved from position 322 to 323, the brush passing over the cutout at 364 which causes a break in the flow of current supplied to the holding winding of magnet P27, permitting the armature 301 to fall off. This unlocks coordinate bar 31—32 on the subsidiary grid and permits it to return to its original position.

Reference has been made above to motor element 1 on the main coordinate grid. An element of this grid is shown in Figs. 4 and 5. Like the subsidiary grid of Fig. 3 it consists essentially of two sets of bars (this term being used in its wider sense, and not limited to any particular 115 geometric shape), action being produced when one bar in each set has moved. When magnet 815 is energized, it attracts armature 816 causing bar 825 to move to the left, which also moves to the left the movable members 819 and 820 held in the position shown in the drawings by springs 821. If a bar in the other set, such as 823, moved from its position shown downwards, nothing would happen, but if bar 825 were moved to the left first, 823 would strike the projection 125 824 and thereby move 819 down, pulling down 817 which is one of the levers on the printing typewriter, this in turn producing an impression of the proper character on the paper tape or page.

As set forth above, the second impulse caused 130 the motor element 1 to operate, this motor element being represented in Fig. 4 by 815. If no other provision were made, the armature 816 would have returned to its original position under the action of spring 828 as soon as the current through 815 has been broken, and the apparatus would have become inoperative. To prevent this, a detent has been provided, this consisting of bar 827 provided with shoulder 829 and swivellingly attached to post 836. When 825 moves forward, it carries with it catch 830 which in due time engages with the shoulder 829 and does not permit bar 825 to move back until 827 has moved to an extent sufficient to release 830.

Two impulses have therefore been used up; the 145 subsidiary grid is in its original position; coordinate bar 1 on the main grid is held in its operative position by a detent, and the commutators are in the following positions: 77; 333; 323; 433; 533; 633; 57. The next pair of impulses are N—P. 150

When impulse N comes in, the following circuit is established by the closing of the switch at 34: 34 to 35 to 36, over 29 to 57, to N55 operating bar 58—56; thence by wire 28 to 22, to 495 to SMS (closing the circuit of SM in the manner previously described) to 34 completing the circuit. When N55 has been energized, it pulled over armature 359 which closed the circuit at 360, so that now the current is flowing 10 as follows: 360 to 395 to 305 to 323 to 302 to 307 to 44 to 495 to 22 to 28 to N55 closing the circuit and providing the holding current for N55. Such a holding current is provided every time a first-operated bar is used on the subsidiary 15 grid, and will not be described in detail hereafter. Bar 56—58 is now held in its operative position. Next, SM moves all the commutators one step forward, into the following positions: 60; 324; 334; 434; 534; 634; 358. Three impulses have 20 been used up; one of the bars on the main grid is locked in its operative position, and so is one bar (58—56) on the subsidiary grid.

Next comes impulse P establishing the following circuit: 21 to 23 to 24 to 60 over 25, to P61 25 moving coordinate bar on the subsidiary grid 32—56, then by wire 28 to 22, to 495, to SMS to 21. With N55 previously locked, the moving of P61 closes the switch at 56, letting the current to go to 408, to 434 to S—1, the current continuing to 928, and over 28 to 22. S—1 is a magnet and when energized, attracts its armature which closes the switch at 467—468. No current, however, is flowing as the circuit is broken elsewhere in a number of places. A catch is provided to 30 lock the armature of S—1 in attracted position, thus keeping the switch 467—468 closed. The purpose of this operation will appear presently.

Four impulses have now been consumed. Brush 306, in moving over the cutout between 40 324 and 325 broke the holding current on N55, so that the subsidiary is back again in its original position. The commutators are now in the following positions: 59; 335 (no brush); 325; 435; 535; 635; 459. The next pair of impulses are 45 P—P.

The first P impulse closes as before the switch at 21, and establishes the following circuit: 21 to 23 to 24 to 59 to P27 which actuates coordinate bar on the subsidiary grid 31—32, and is locked 50 in position by the second current. SM moves, shifting the commutators to the following positions: 260; 336; 326; 436; 536; 636; 560.

The following impulse is again a P, and the circuit is 21 to 23 to 24 to 260 to P61 which actuates 55 bar 32—56, the current then continuing over 28 to 22, to 495 to SMS and 21. With bar 31—32 locked previously, and 32—56 now moved, the switch at 32 is closed, the current being permitted to flow over 308 and 336 to motor elements 8, 12 60 and 16.

These represent the same kind of bars on the main coordinate grid as are shown as 823 in Figs. 4 and 5. Let us now consider bar 12. The current comes into it over 336, but it cannot get 65 out of it as the switch at 567—568 is open. The same applies to 16, where the switch at 667—668 is open. The current can, however, flow through 8 as the switch at 467—468 has been previously closed and is being held in its closed position by 70 means of a detent. Bar 8 will be therefore operated, and in conjunction with bar 1 in the other set will operate a printing key in the manner shown in Figs. 4 and 5 and previously explained.

As will be now noted, the bars 5 to 16 (four 75 more such bars, 17 to 20, can be installed) are

divided into groups of four, each group controlled by a pre-selector switch or magnet S. The magnet SM acts now, and causes the release into the original position of magnet P27 on the subsidiary grid; it also moves all the commutators into the positions shown in the drawings, and hence makes them ready for handling the next character. Bar 1 and selector S—1 are still, however, in their locked position, and must now be unlocked. The mechanism for doing this is 80 shown in Figs. 4 and 5. There is provided there a bar 833 swingingly supported by legs 831 and 832 and held in the position shown by spring 834. Bar 833 carries a T-shaped piece 826. 835 in Fig. 5 represents the detents of the selectors S, 85 one of which is held thereby in its locked position. The projecting part of 826 is so arranged that when moved down, it would catch the bar 827.

On the last impulse one of the vertical bars 90 (say 8 in Fig. 2, or 823 in Figs. 4 and 5) is moved down, carrying with it 824. If the latter is moved sufficiently far, it will force down 833, the projection 826 depressing 827 until the shoulder 829 is no more engaged with catch 830, whereupon spring 828 pulls back the post to which it is attached, and with it bar 825, placing this latter into its original inoperative position and making it ready for the next cycle of operations. Furthermore, bar 833 in its downward movement 100 depresses the catch 835 of the selector detent, and releases the latter. Magnet 834 corresponds to 8 in Fig. 2.

The movement of 833 may be used to move the tape. The details of this are not shown as any 110 engineer can design the necessary apparatus, or an apparatus similar to that of Fig. 6 may be used.

While in referring to the elements of the coordinate systems, the term "bar" has been used 115 for the sake of convenience, it is specifically desired to disclaim any limitation thereby of the term as limited by any geometric shape of the elements so employed, the intention being simply to refer to parts of apparatus wherein interaction 120 can be produced only as a result of a motion other than that of simply-additive vectors.

I claim:

1. Apparatus comprising two devices, each responsive to a particular kind of electric impulses; 125 two switches each controlled by one of the single-type-impulse-responsive devices; a source of electrical energy controlled by said switches and other than the impulses above referred to; symbol impressing means; a system of two sets of 130 coordinate bars and means to operate separately each one of said bars, means operable by the cooperation of any one bar in one set of said coordinate bars with any one bar in the other set, said means themselves operating the symbol-impressing devices; means to divide the desired 135 set of coordinate bars into groups, and means to supply energy only to a selected group of coordinate bars, and to a selected motor element actuating a bar in said selected group, said means comprising a subsidiary set of coordinate bars 140 wherein the cooperation of a member of one set with a member of the other set causes the closing of a switch, and a system of single-path commutators moving simultaneously and through 145 the same part of the cycle, together with means to move said commutators one step for each electrical impulse received by one of the impulse-sensitive devices; of said commutators four having means to provide a path of flow of energy, 150

- on the second impulse to the motor element operating the selected member of the first-operated set of the main coordinate bars; on the fourth impulse to the selected unit of the apparatus each 5 unit of which controls the admission of energy to one group of the second-operated set of the main coordinate bars, and on the sixth impulse to the selected members of the second set of the main coordinate bars.
- 10 2. Apparatus as set forth in claim 1, wherein the means to move the commutators become operable only upon the cessation of the impulse herein referred to.
3. Apparatus as set forth in claim 1 wherein 15 two of the commutators are so connected with the impulse-sensitive devices that each one of said commutators is traversed by an electric current only subsequently to the response of the impulse-sensitive device to which said commutator is connected, the current traversing the commutator being from a source other than the impulse.
4. Apparatus as set forth in claim 1, wherein the commutators are moved by a motor element 25 fed by a current from a source other than the signalling impulse, said current being delivered through a switch controlled by either of the impulse-sensitive devices.
5. Apparatus as set forth in claim 1, wherein 30 the commutators are moved by a motor element fed by a current from a source other than the signalling impulse, said current being delivered through a switch whereof the closing and opening is in turn controlled by a switch controlled by either of the impulse-sensitive devices.
6. Apparatus as set forth in claim 1, wherein 35 the coordinate bars in both the main and the subsidiary sets are divided into first-operated and second-operated members, and means are provided to hold the first-operated bar in each set in its operable position until released subsequent to the operation of the second-operated bar.
7. Apparatus as set forth in claim 1, wherein 40 the coordinate bars are divided into first operated and second operated members, and means are provided to hold the first-operated bar in its operable position until released subsequent to the operation of the second-operated bar, the means operating the first-operated bar being an electromagnet with means to impress upon it a current subsequent to the response to a signalling device, said current ceasing to flow before the next signalling impulse comes in, a switch operated by 45 said electromagnet, a source of current independent of the signalling impulse, an armature operable when a current is flowing through the electromagnet, means to hold the coordinate bar in its operable position by the armature when the latter is attracted by the electromagnet, means to close the switch by the armature when in its attracted position, means to admit thereby a current to the electromagnet, and means to cut off 50 this current in the appropriate part of the cycle by means of a commutator wherein the path for the circuit is broken during the period when the brush passes from one rest position to another rest position.
- 75 8. Apparatus as set forth in claim 1, wherein the coordinate bars are divided into first-operated and second-operated members, and means are provided to hold the first-operated bar in its operable position until released subsequent to the 80 operation of the second-operated bar, the operable and holding means comprising an electromagnet with two windings, a source of current other than the line impulses, means to admit the current to one of these windings, an armature 85 attractive to the electromagnet thereupon, a switch closing when the armature is attracted and means to admit thereby current to the second of said windings, said current continuing to flow after the current in the first winding has ceased to flow, means to hold the bar in its locked position by the armature when the latter is held attracted to the electromagnet, and means to break the current flowing through the second winding in the appropriate part of the cycle by means of a commutator wherein the path for the current is broken during the period when the brush passes from one rest position to another rest position.
9. Apparatus as set forth in claim 1, comprising a commutator providing a path for the flow of current at all times except when said flow is broken once in every two steps, the break occurring while the commutator is being moved from one rest position to another.
10. Apparatus as set forth in claim 1, comprising a subsidiary system of coordinate bars wherein in the cooperation of any bar in one set with any bar in the other set closes a switch in a circuit wherein by the first two impulses for each character there is actuated the selection of one motor element in the first set of the main coordinate 100 bars; by the second set of impulses, the selection of a group in the second set of the main coordinate bars, and by the third pair of impulses, the selection of a row in the second set of the main system of coordinate bars; together with means to prevent the actuation of any of the motor elements in the row selected by the third pair of impulses except the one in the group selected by the second pair of impulses.
11. Apparatus as set forth in claim 1, mechanical means to lock the desired element in its operable position until released, a system of coordinate bars comprising movable elements and means to move these movable elements part of the way by a bar in one set and a further part of the way 105 by the bar from the other set; a movable element so located that when moved it releases the locking means of the element previously locked, and also so located that it is moved through a predetermined distance by the movable elements operated by the coordinate bars when the bars of both sets have moved their assigned distances.
12. Apparatus as set forth in claim 1, and means to move the strip whereupon the symbols are impressed, said means comprising in the system main coordinate bars of movable elements forming part thereof; means to move these movable elements part of the way by a bar in one set and a further part of the way by the bar from 110 the other set; another movable element so located that it is moved through a predetermined distance by the movable element operated by the coordinate bars when the bars of both sets have moved their assigned distances; a circuit whereby the main coordinate bars are thus moved once for every character, and means to transmit the movement of the second movable element to the strip causing it to move one step for each character transmitted.
13. Apparatus as set forth in claim 1 wherein the coordinate bars are divided into first-operated and second-operated members, and means are provided to hold the first-operated bar in its operable position until released subsequent to the 115 140 145 150

- operation of the second-operated bar, the means 5
operating the first-operated bar being an elec-
tromagnet with means to impress upon it a cur-
rent subsequent to the response to a signalling
impulse by the proper impulse-sensitive device,
said current ceasing to flow before the next sig-
nalling impulse comes in, a switch operated by
said electromagnet, a source of current other than
the signalling impulse, an armature operable
10 when the current is flowing through the electro-
magnet, means to hold the coordinate bar in its
operable position by the armature when the latter
is attracted by the electromagnet, means to close
the switch by the armature when in its attracted
15 position, means to admit thereby a current to
the electromagnet, the resistance of the circuit
of said secondly admitted current being material-
ly greater than the resistance of the circuit of the
firstly admitted current.
20 14. Apparatus as set forth in claim 1, wherein
the coordinate bars are divided into first-oper-
ated and second-operated members, and means
are provided to hold the first operated bar in its
operable position until released subsequent to its
25 the operation of the second operated bar, the
operable and holding means comprising an elec-
tromagnet with two windings, a source of current
other than line impulses, means to admit the
current to one of these windings, an armature
attractable to the electromagnet thereupon, a
switch closing when the armature is attracted,
80 and means to admit thereby current to the sec-
ond of said windings, the resistance of the cir-
cuit embodying the second winding being mate-
rially greater than the resistance of the circuit
through the first winding, together with means to
85 hold the bar in its locked position by the arma-
ture when the latter is attracted by the electro-
magnet.
15. Apparatus as set forth in claim 1, an elec-
tromagnet to move the commutators one step
for each impulse, said electromagnet being in
a circuit parallel to that operating the motor
elements of the main and subsidiary coordinate
90 bar systems, and a switch controlling the admis-
sion of energy to said electromagnet operable by
an electromagnet in series with the motor ele-
ments moving the bars and other movable units
of the main and subsidiary systems of coordinate
95 bars.
